(57) **CLAIM**

The ornamental design for scissors, as shown and described.

DESCRIPTION

FIG. 1 is a right side view of the scissors;

FIG. 2 is a left side view of the scissors;

FIG. 3 is a front view of the scissors;

FIG. 4 is a rear view of the scissors;

FIG. 5 is a top view of the scissors;

FIG. 6 is a bottom view of the scissors;

FIG. 7 is a right side view of the scissors with the blades open;

FIG. 8 is a section view taken along the line A-A of FIG. 1 of the scissors;

FIG. 9 is a perspective view of the scissors; and,

FIG. 10 is a perspective view of one part of the scissors. The broken lines of the hand illustrate the environment in which the article embodying the design is used and form no part of the claim.
